UNITED STATES PATENT OFFICE.

HARRY DILYOCK, OF BOSTON, MASSACHUSETTS, ASSIGNOR OF ONE-HALF TO JACOB SMITH, OF BOSTON, MASSACHUSETTS.

LOCKED-COP-TUBE HOLDER.

1,104,172.

Specification of Letters Patent.

Patented July 21, 1914.

Application filed November 28, 1913. Serial No. 803,510.

To all whom it may concern:

Be it known that I, HARRY DILYOCK, a citizen of the United States, and a resident of Boston, in the county of Suffolk and 5 State of Massachusetts, have invented an Improvement in Locked-Cop-Tube Holders, of which the following description, in connection with the accompanying drawings, is a specification, like characters on the 10 drawings representing like parts.

This invention relates to an apparatus especially designed for use with sewing machines and the like, to prevent loss of thread by the removal of partially exhausted rolls 15 of threads and more particularly silk thread from the spindles on which they are mounted. To this end, the spindle carrying the roll of thread is mounted on a post extended from a suitable support, and said spindle 20 is locked on said post against removal by unauthorized persons. The post may be attached to a base plate which is capable of being fastened to machines now built, and a cap plate is provided to conceal the fastening 25 means, which is locked by means of a sleeve retained on the post by the spindle. These and other features of this invention will be pointed out in the claims at the end of this specification.

30 Figure 1 represents in elevation a sufficient portion of a sewing machine provided with roll holder embodying this invention. Fig. 2, an elevation on an enlarged scale of the roll holder shown in Fig. 1. Fig. 3, a 35 vertical section and elevation of the holder shown in Fig. 1. Fig. 4, a detail in section to be referred to, and Fig. 5, a detail in plan to show the cap plate in position.

In the present instance, one embodiment 40 of the invention is shown, which is especially designed for use with sewing machines employed in factories, which are supplied with thread and especially silk thread from a roll *a* wound upon a cop or tube *b*.

45 The tube or cop *b* is mounted on a spindle *c* provided at one end with a head *d* and at its other end with a hole *e*, through which is extended an upright post 10 extended from a base plate 12, which is designed to be 50 secured as by screws 13 to the head 14 of a sewing machine of known construction and such as now commonly used in factories. The spindle *c* is secured in fixed relation to the post 10 by a set screw 16. Provision is 55 made for locking the cop tube spindle *c*

against removal from the post 10, and also for locking the base plate 12 against removal from the head 14 of the sewing machine. The base plate 12 may be locked against removal from the head 14 of the sewing machine, by a cap plate or bar 20, which is pivoted at one end as at 22, to a plate or bar 23 riveted to or forming part of the base plate, and has its other end provided with a slot 24, see Fig. 5, which forms arms 25, 60 which straddle the post 10 and upon which rests the lower end of a metal tube or sleeve 27, which is fitted loosely on the upright post 10 and is retained thereon by the spindle *c*. The metal sleeve 27 may be cut away 65 at its upper portion as at 28, so as to enable the end of the cop tube *b* to be extended close up to the upright post 10.

The spindle *c* is locked on the post 10 by means of a locking device, which is passed 70 through a hole 30 in the post 10 near the upper end thereof and above the spindle *c*. In the present instance the locking device is shown as a padlock 31, whose hasp 32 is passed through the hole 30 in the post 10. 75 The sleeve 27 serves a two-fold purpose, in that it serves as a support for the spindle *c* and relieves the set screw 16, and also serves as a lock for the cap plate 20. The set screw 16 serves to keep the spindle *c* from 80 turning on the post 10. The cap plate 20 prevents access to the screws 13 or other means by which the base plate 12 is fastened to its support, thereby preventing the device being bodily removed. The base plate 85 12 may and preferably will be provided with a second post 35, which is provided with an eye 36 for the passage of the thread 37, and which supports a tension device 38 of usual or known construction. The base plate 90 12 may also be provided with a third substantially short post 40, which serves as a stop for the thread as it is unwound from the roll, and prevents the thread from becoming tangled up with the tension device. 95

The apparatus herein shown is adapted to be secured to sewing machines now used in large numbers, in factories and like places, and is readily applied by tapping into the head of the machine, suitable holes 41 for 100 the reception of the screws 13 which can be screwed into said holes, after the cap plate 20 has been turned back so as to uncover said holes. After the base plate 12 has been secured to the machine head 14, the cap 105 110

plate 20 is turned down so as to cover the screws as represented in Figs. 3 and 5, the sleeve 27 is then slipped over the post 10, the spindle *c* with the roll *a* thereon is 5 then slipped over the post 10, and the hasp 32 is passed through the hole 30 and locked by a suitable key (not shown). The spindle *c* is then turned so as to bring it above and into the plane of the 10 base plate, and is then secured against turning on the post 10 by the set screw 16. While the spindle *c* is locked on the post 10, the roll *a* of silk thread can not be removed from the spindle *c* by the operator or any 15 other unauthorized person, and as a result, a very considerable saving in silk is obtained for the manufacturer, and the temptation for the operative to waste material by removing a roll of the silk thread before it 20 has been used up, is avoided.

In the present instance, the base plate 12 is shown as separate from the machine, so that it can be applied to machines now in use, but it is not desired to limit the invention 25 in this respect, as it is evident that in manufacturing a new machine head 14, the post 10 may be cast integral therewith, in which case the base plate 12 and cap plate 20 would be dispensed with, and the lock 30 for the spindle *c* alone retained.

The head 14 of the sewing machine forms one form of support for the device, but it is not desired to limit the invention in this respect, as the post 10 may be secured to 35 any form of support, such as a bench, wall or upright, in proximity to the sewing machine. Furthermore, it is not desired to limit the invention to the use of a padlock as a lock for the spindle *c*.

40 Claims:

1. In an apparatus of the character described, a base plate provided with holes for the reception of screws by which the base plate is fastened to a support, a post 45 extended from said base plate and provided with a hole, a cap plate hinged to said base plate and provided with arms which straddle said post, said cap plate covering the screw holes in the base plate, a sleeve loose 50 on said post and bearing on the arms of said cap plate, a spindle for the roll of thread mounted on said post, said spindle having at one end a head and near its other end a hole for the passage through it of said 55 post, a locking device extended through the

hole in the said post, and means for securing the said spindle in fixed relation to said post, substantially as described.

2. In an apparatus of the character described, 60 a base plate, means for securing the base plate to a support, a cap plate to cover said means, a post extended from the base plate and provided with an opening through it, a spindle for a roll of thread mounted 65 on said post, said spindle having at one end means for retaining the roll thereon and at its other end a hole for the passage through it of said post, a sleeve on the said post to support said spindle and to lock said cap 70 plate, and a locking device for said spindle extended through the hole in the post, substantially as described.

3. In an apparatus of the character described, 75 a base plate, means for securing the base plate to a support, a cap plate to cover said means, a post extended from said base plate, a sleeve on said post to lock said cap plate against removal, a spindle extended 80 from said post and removable therefrom and coöoperating with said sleeve to retain it on said post, and means to lock said spindle on said post, substantially as described.

4. In an apparatus of the character described, 85 a base plate, means for fastening it to a support, a cap plate to cover said fastening means, a post extended from said base plate, a spindle mounted on said post and extended therefrom at an angle thereto, means interposed between said spindle and 90 cap plate to lock the latter, and means to lock the spindle on said post against removal by unauthorized persons.

5. In an apparatus of the character described, 95 a base plate, means for fastening it to a support, a cap plate to cover said fastening means, a post extended from said base plate, a sleeve mounted on said post to lock said cap plate, a spindle mounted on said post beyond said sleeve and extended 100 from said post at an angle thereto, and means to lock said spindle on said post against removal by unauthorized persons, substantially as described.

In testimony whereof, I have signed my 105 name to this specification in the presence of two subscribing witnesses.

HARRY DILYOCK.
